UNITED STATES PATENT OFFICE

107,384

DESIGN FOR A DOOR FOR A HEATER CABINET OR THE LIKE

Mervin F. Cotes and Walter C. Schneider, Lansing, Mich., assignors to Motor Wheel Corporation, Lansing, Mich., a corporation of Michigan

Application May 10, 1937, Serial No. 69,279

Term of patent 3½ years

To all whom it may concern:

Be it known that we, Mervin F. Cotes and Walter C. Schneider, citizens of the United States, residing at Lansing, in the county of Ingham and State of Michigan, have invented a new, original, and ornamental design for a Door for a Heater Cabinet or the like, of which the following is a specification, reference being had to the accompanying drawing, forming a part thereof.

In the drawing:

Fig. 1 is a front elevational view of a door for a heater cabinet or the like embodying our new design;

Fig. 2 is a sectional view taken on the line 2—2 of Fig. 1;

Fig. 3 is a sectional view taken on line 3—3 of Fig. 1; and

Fig. 4 is a sectional view on the line 4—4 thereof.

We claim:

The ornamental design for a door for a heater cabinet or the like as shown.

MERVIN F. COTES.
